(57) **CLAIM**

The ornamental design for a mat for toddler strollers, as shown and described.

DESCRIPTION

1 . Mat for toddler strollers

1.1 : Perspective

1.2 : Top

1.3 : Front

1.4 : Right

1.5 : Bottom

1.6 : Top folded

1.7 : Front/back folded

1.8 : Bottom folded

1.9 : Side folded

1.10 : Top semi folded

The design is of a foldable mat for toddler strollers; the drawings show the design in an open position and in a folded position. The broken lines shown in FIGS. 1.1-1.10 are directed to environment and are for illustrative purposes only; the broken lines form no part of the claimed design.
